UNITED STATES PATENT OFFICE

LOUIS KESSLER, OF CHICAGO, ILLINOIS

MINE-VENTILATING SYSTEM

Application filed October 24, 1927. Serial No. 228,161.

The present invention has for its object to produce a simple and novel mine ventilating system that may be easily controlled and be capable of ready extension as the digging in 5 a mine progresses.

The various features of novelty whereby my invention is characterized will herein-after be pointed out with particularity in the claim; but, for a full understanding of my 10 invention and of its objects and advantages, reference may be had to the following detailed description taken in connection with the accompanying drawings, wherein:

Figure 1 is a vertical section through the 15 shaft of a mine equipped in accordance with the present invention; Fig. 2 is an elevation of a fragment of one of the branch flues and the adjacent end of a flexible collecting conduit detachably connected thereto; Fig. 3 20 is a horizontal section through the mine at one of the levels in which work is being done; Fig. 4 is a view partly in elevation and partly in section, on a larger scale than Figs. 1 and 3, of a fragment of my improved system; Fig. 5 is an elevation of the upper end 25 of the flue, with its protective housing shown in section; and Fig. 6 is a longitudinal section, on a larger scale, through the upper end of the flue.

Referring to the drawings, A represents 30 the shaft of a mine, and B, C and D passages to different working levels with which the shaft is connected. As shown in Fig. 3, a passage may lead to a room E out of which are open pockets F, G and H, or there may 35 be other pockets or passages opening from the passage B, as indicated at I. It will be understood, of course, that the illustration of the mine is simply conventional, for the purpose of explaining the problems which the 40 present invention is to solve, and the manner of solving them.

The main portions of the various working 45 levels normally contain pure air; the objectionable gases being found in pockets or stub ends. Therefore, while it is my purpose to permit objectionable gases to be removed from any part of a mine, it is particularly intended to make it possible quickly 50 and easily to remove gases from pockets or

other spaces which normally are unsafe because of the presence of such gases.

In accordance with my invention, I provide a vertical flue 1 extending from the bottom of the mine shaft to a point considerably 55 above the surface. Lateral pipes 2 lead from the flue into the various levels of the mine; there being, in the arrangement shown, one lateral pipe for each level. In each pipe, preferably adjacent to the flue, is an enlargement 3 constituting a fan chamber in which is mounted a suitable fan 4. These fans are preferably driven electrically, each being governed by a local switch or controller 5. Therefore any or all of the fans may be in 60 operation at one time, or all may be idle. As illustrated in Fig. 3, the pipes 2 may be provided with branches, as indicated at 6 and 6, the number, length, and disposition of such branches depending upon the nature of the 70 cavity at that particular level. The pipes 2, with their branches, are sealed; but they are provided with capped openings to which flexible collecting conduits may be attached, so that there will be no dissipation of the 75 energy of the fans or blowers through drawing in air at points where there are no gases requiring removal. The flexible collecting conduits 7 may consist of sections of hose each provided at one end with a fitting 8, as 80 best shown in Fig. 2, to be interchanged with one of the caps that normally close the openings in the pipes. The fittings may be in the form of sockets adapted to slip over a tubular neck 9 on the pipe and be locked 85 thereto by a simple pin and bayonet slot joint 10. The free end of each flexible conduit is provided with a perforated head 11 that will prevent the passage of flame between the interior of the conduit and the surrounding 90 space and will also prevent large objects from entering the ventilating system.

The pipes are provided with these inlets covered by caps 12 at distributed points along the same, so that there will always be 95 an inlet opening close enough to a pocket from which gases are to be withdrawn, to permit the attachment of a collecting device reaching into such pocket or space.

Since the gases to be removed are of a 100

combustible nature, I prefer to place at the top of the flue a burner that will cause these gases to be consumed instead of being discharged into the open air. As best shown in Fig. 6, I have mounted on the upper end of the flue a small reservoir 13 having in the bottom perforations 14 through which the gases may rise. The top or cover of the reservoir contains a central chamber 15 having in the bottom an opening 16 and in the top an opening 17. A pipe 18 for supplying gas extends up beside the upper end of the flue and is connected to a port 19 that opens into the chamber 15. When gas is flowing through the pipe 18, it may be ignited in the chamber 15, thereby constituting a pilot light that will ignite combustible gases driven upwardly through the flue.

In order to prevent backfiring through the flue, I prefer to place in the upper end, below the reservoir 13, a plurality of frustoconical screens 20 whose large ends fit tightly in the flue. These screens do not interfere with the upward travel of the gases, while preventing the flame at the top from igniting the gases below the screens.

The top of the flue may be enclosed within a suitable housing 21 to protect it against the weather.

The pipes are preferably made of comparatively light material. Therefore, to prevent them from collapsing on account of too great a drop of pressure within the same, I provide each pipe with a safety valve, preferably located near the fan and on the suction side of the fan; whereby, when the pressure in the pipe drops too low, the safety valve will open and permit air to be drawn in. These safety valves may take any suitable form. In the arrangement shown, as best illustrated in Fig. 4, each valve comprises a casing 22 that constitutes a short section of the pipe; this casing having on one side a dome 23 provided with a perforated top 24. Within the dome is an outwardly seating valve 25 held closed by a suitable spring 26. When the pressure in the pipe drops below a predetermined maximum, the valve opens, thereby preventing the pressure from becoming low enough to endanger the integrity of the pipes.

While I have illustrated and described with particularity only a single preferred form of my invention, I do not desire to be limited to the exact structural details thus illustrated and described; but intend to cover all forms and arrangements which come within the definitions of my invention constituting the appended claim.

I claim:—

An apparatus for ventilating mines, comprising a vertical discharge flue leading to the surface from the depth of a mine, sealed lateral pipes of light material connected to said flue at various levels, a fan in each of

said pipes near said flue arranged to discharge into said flue, a safety valve in each pipe on the suction side of the corresponding fan to admit air or gas into the pipe when the pressure in the latter drops below a predetermined value, and gas-collecting means adapted to be connected to any one of said pipes.

In testimony whereof, I sign this specification.

LOUIS KESSLER.
